UNITED STATES PATENT OFFICE.

SANFORD E. MANNING, OF WEST COLUMBIA, TEXAS.

MEANS FOR MOVING THE DRIVE-SHAFTS OF STEAM-ENGINES FROM DEAD-CENTERS.

1,390,536.

Specification of Letters Patent. Patented Sept. 13, 1921.

Application filed August 21, 1920. Serial No. 405,138.

To all whom it may concern:

Be it known that I, SANFORD E. MANNING, a citizen of the United States, residing at West Columbia, Brazoria county, Texas, have invented a certain new and useful Improvement in Means for Moving the Drive-Shafts of Steam-Engines from Dead-Centers, of which the following is a full, clear, and exact description, such as will enable others skilled in the art to which it appertains to make and use the same.

My invention relates to an improvement in means for moving the drive shaft of steam engines from dead center. This device is particularly adapted for use on engines in oil field work, but is obviously capable of wide application, and is not, therefore, confined to this particular use.

In the oil field work where the laborers are usually engaged in work upon the derrick platform, it is customary to place the engine in a position spaced somewhat to one side of the derrick. In the operation of the drill or of the cable it is frequently necessary to stop and start the engine in the progress of the work. It is found that the engine will sometimes stop on dead center, that is the cross head pin, the crank pin and the crank shaft will be in alinement so that when the steam is turned on to start the engine no movement of the power shaft will result. To draw the parts off dead center it is usually necessary for one of the men to leave the platform, go to the engine and, by rotating the fly wheel, turn the shaft until the parts are no longer in alinement. This operation takes time during which the drilling crew is standing idle.

The object of my invention is to provide a device whereby the crank shaft of the engine may be moved from dead center and such operation may be performed from a distance by the simple manipulation of a lever situated on the derrick platform or at some convenient position.

Another object is to provide a device of the kind described which will be simple and durable in construction, easy to operate and not liable to get out of order.

In the drawing herewith, constituting a part of this specification, a preferred embodiment of my invention is shown. Figure 1 is a side view showing the shaft of the engine in transverse section with my improvement applied thereto. Fig. 2 is a broken

view in elevation showing my device applied thereto. Fig. 3 is a view of the lever used in operating my device. Fig. 4 is a modified form thereof. Fig. 5 is a side elevation of the lever used in connection with my device 60 and Fig. 6 is a side elevation of a modified form of my improvement.

My device is designed as an attachment for the power shaft of the engine, whereby the said shaft may be rotated by means of a 65 lever situated at some convenient point at a distance from the said power shaft. In accomplishing this purpose, I contemplate placing upon a power shaft 1 of an engine, and closely adjacent the fly wheel 2 thereof, 70 a ratchet wheel 3, said ratchet wheel having teeth 4 thereon, one side of which is radial and the other side forming an angle of about 45° to the first mentioned side. The ratchet wheel has a laterally extending hub 75 5 thereon, said hub and ratchet wheel secured non-rotatably on said shaft 1 by means of a key 6.

Seated rotatably upon the said hub 5 of the ratchet wheel is placed a lever or arm 80 7, said lever having at the pivoting end thereof a ring 8 adapted to fit slidably over the end of the hub and to be rotatable thereon. The arm of the lever 7 extends upwardly from said engine shaft, preferably 85 at an angle from the vertical. Said arm has, at a suitable point thereon, a pivoted pawl 9 secured to the said arm at 10. This pawl has a sharp downwardly presented point which is adapted to fit between two adjacent 90 teeth 4 upon the ratchet wheel. The opposite end of the pawl 9 is extended beyond the lever arm 7 and is provided with an opening therein for attachment of a cable 25 to be later described. Spaced upwardly from the 95 said pawl is a supporting member 11. This support constitutes a strap of metal projecting laterally from the arm of the lever to a point over-hanging the pawl 9. Secured at the lower end of the support 11 is a spring 100 12 connected at its opposite end to the upper outer side of the pawl 9. This spring is under tension and acts normally to hold the said pawl upwardly out of contact with the teeth 4 of the ratchet wheel.

The lever 7 is operated by means of a tubular connecting bar 14. Said bar is secured at one end to the lever 7 by means of a yoke 15, said yoke being threaded upon the end of the tubular bar and having two laterally 105 110

projecting arms thereon which are formed to straddle the end of the lever 7 and to be secured pivotally thereto by means of a pin 16. The opposite end of the tubular bar 14 5 has a similar yoke 17 thereon, which is pivoted by means of a pin 18 to an operating lever 19 approximately midway of said lever. The upper face of the tubular bar 14, at a point spaced somewhat from the lever 10 19, is provided with an upwardly extending nipple 20, in the lower portion of which is pivoted a pulley or roller 21.

Spaced somewhat from the upper end of the lever 19 is a short releasing lever 22 pivoted at 23 to the operating lever 19. On the lower face of said releasing lever is secured at 24 the operating cable 25. Said cable passes downwardly through the open end of the nipple 20, around the pulley 21, and longitudinally through the tubular operating bar 14, and around a roller 26 in the upper end of the lever 7. From thence it passes downwardly for attachment to the pawl 9, as previously indicated. It will thus be noted 25 that the tightening of the cable 25 will act to draw the pawl 9 downwardly against the action of the spring 12. The lever 19 is ordinarily placed upon the edge of the derrick platform, to which it is pivoted by means of 30 a bolt or pin 28.

In Fig. 5 I have shown a slightly different arrangement of the operating means for the pawl 9. In this modification the pawl is not extended beyond the arm 7 of the lever, 35 but in place thereof the supporting member 11 is extended on the opposite side of the said lever 7 to provide a support for a roller 13. Another similar roller 27 is pivoted on the lever arm 7 at a point below the pawl 9. 40 The lower edge of the pawl 9 is perforated to provide an attachment for the cable 25. In this arrangement the cable acts directly to draw the pawl 9 down against the action of the spring 12 and when the pull upon the 45 cable is released the pawl 9 will be drawn upwardly by the spring.

It is contemplated that other operating means may be used besides the lever 19 and in Fig. 4 another operating means is shown. 50 To the outer end of the tubular bar 14 is secured a stirrup, 29, having at the extremity thereof a handle 30, between the two arms of the stirrup. Spaced between the arms of the stirrup and inwardly from the handle 30 55 is a slidable bar 31, to the central point of which is secured the cable 25.

The operation of my device will now be clearly understood. When the shaft of the engine stops with the parts on dead center, 60 the operator on the derrick platform will grasp the lever 19, his fingers gripping about the releasing lever 22. By the closing of his fingers upon the lever the releasing lever will be drawn up, thus pulling the cable 25 65 so as to draw the pawl 9 downwardly into

coöperation with the ratchet teeth 4 upon the ratchet wheel. A further pull upon the lever 19 will draw the connecting bar 14 so as to throw the lever 7 toward the operator. The pawl 9, being in contact with the ratchet teeth, will throw the shaft over toward the operator, thus throwing the parts from dead center and allowing the shaft to be rotated. It is obvious that as the shaft begins to rotate under the impulse of the engine the 75 pawl 9 will be drawn out from its contact with the teeth 4 and the operator, by releasing the cable 25, through the releasing lever 22, will allow the pawl to be drawn up out of operative position. The lever 19 may then 80 be thrown forwardly out of the way and will be ready for use at any future time.

If the operating lever shown in Fig. 4 is used, the operator, in grasping the handle 3, will seize also the slidable bar 31, drawing it 85 toward the operating handle 30, thus withdrawing the cable 25 and operating to draw the pawl 9 into operative position and a further pull upon the handle 30 will draw the lever 7 so as to rotate the shaft 1.

In Fig. 6 I have shown a modified form of my device, in which the parts are somewhat simpler than in the preceding embodiment, but the operation thereof conforms in general principle to that just described. In this embodiment the lever or arm 7' is journaled upon the hub 5 of the wheel, as previously shown, but a bushing 32 is included between the ring 8' and the hub 5 to form a better bearing upon which 100 the lever may turn. The part of the ring 8' opposite the lever 7' is extended downwardly to form an arm 33 which is limited in its movement laterally by means of a stop member 34, which is secured to some convenient 105 support by means of pins 35. The stop member 34 has two upwardly projecting arms 36 against which the arm 33 of the lever is adapted to contact at the extreme points in the movement thereof.

The pawl 9' in this modification is pivoted at 10' toward the upper end of the lever arm 7' and has a backwardly extending lug 37 on the upper face thereof, said lug being adapted to contact with a laterally extending lug 38 on the upper end of the lever arm 7' when the pawl is in inoperative position. The pawl 9' on the side of the lever opposite the point thereof has an upwardly extending arm 39, having a pin 40 on the said upper 120 end, to which the rod 14' is pivoted.

The said rod 14' connects the operating arm 39 of the pawl with the lever 19' pivoted at 28 on the derrick platform. This lever 19' has a laterally extending lug thereon, to which is pivoted at 18' the other end of the rod 14'. The lever 19' has, below the attaching point 18' thereof, an opening 41 therein through which the upper end of a spiral spring 42 is secured. The lower end 130

of the said spring 42 is secured to a staple 43, which is anchored in some convenient support adjacent the derrick platform. The spring 42 is under tension and tends to 5 throw the lever 19' to the left, as shown in Fig. 6.

In the operation of this embodiment the lever 19' on being released will be thrown by the spring to the left and thereby throws 10 the upper arm 39 of the pawl also to the left, bringing the lug 37 into contact with the lever arm 7' and throwing said lever to the left and releasing the pawl 9' from the ratchet wheel. The lever arm 7' will be 15 thrown to the left until the lower arm 33 contacts with the stop arm 36, thus leaving the pawl 9' out of contact with the ratchet wheel. When it is desired to rotate the ratchet wheel and the shaft 1 upon which it 20 is fixed, the lever 19' will be thrown to the right, thus throwing the pawl 9' into contact with the ratchet wheel and the movement of the lever arm 19' will then rotate the ratchet wheel sufficiently to throw the parts from 25 dead center. It is contemplated that the lever arm 19' can be thrown to the right until the arm 33 of the lever 7' will contact with the opposite stop arm 36. This will be sufficient to accomplish the object of starting 30 the engine. The lever 7' may then be released and the spring will draw it to the left until the lever arm 33 of the lever 7' contacts with the forward stop arm 36, thus holding the pawl 9' in inoperative position. 35 It is apparent that with the use of this device a great saving in time will result, as the engine may be started by simply pulling upon the lever directly from the derrick platform and thus obviating the necessity 40 of the laborer going from the derrick to the engine to throw the same from dead center.

Having thus described my invention, what I claim as new and desire to protect by Letters Patent is:

45 1. A device of the kind described comprising a power shaft, a ratchet wheel keyed thereon, a laterally projecting hub on said ratchet wheel, a lever pivoted on said hub and rotatable independently of said wheel, 50 a pawl pivoted on said lever and held normally out of contact with said ratchet wheel, a tubular connecting bar secured at one end of said lever, an operating lever secured to the other end of said connecting bar, a pivoted releasing lever on said operating lever and a cable connecting said pawl with said

releasing lever to force said pawl into co-operation with said ratchet wheel.

2. A device of the character described comprising a power shaft, a ratchet wheel keyed 60 thereon, a lever pivoted about said shaft adjacent said wheel, a pawl pivoted on said lever and held normally out of contact with said ratchet wheel, a tubular connecting bar secured to said lever, an operating lever 65 secured to said bar, a releasing lever and a cable connecting said pawl with said releasing lever and acting to force said pawl into co-operation with said ratchet wheel.

3. A device of the character described comprising a power shaft, a ratchet wheel keyed 70 thereon, a lever adjacent said ratchet wheel and rotatable independently thereof, means on said lever to engage said wheel, an operating lever, a tubular bar connecting said 75 operating lever with said first named lever, and means on said operating lever to actuate said ratchet-wheel-engaging means in the manner described.

4. A device of the character described comprising a power shaft, a ratchet wheel keyed 80 thereon, a lever adjacent thereto, a pawl on said lever, means to hold said pawl normally out of contact with said ratchet wheel, an operating lever, means connecting said operating lever with said first named lever, and means on said operating lever to force said pawl into engagement with said ratchet 85 wheel, whereby said wheel may be rotated.

5. A device of the character described comprising a power shaft, a ratchet wheel fixed 90 on said shaft, a lever adjacent said wheel, an operating lever spaced from said shaft, a rigid means connecting said operating lever with said first named lever, whereby the 95 latter may be thrown either backward or forward and means to connect said first named lever with said ratchet wheel and operable from said operating lever.

6. A device of the character described comprising a power shaft, a ratchet wheel fixed 100 thereon, a lever adjacent said wheel, a connecting bar pivoted to the outer end of said lever, means to move said bar and operate said lever, in both backward and forward 105 directions, and means to connect said ratchet wheel and said lever operable independently of said lever operating means.

In testimony whereof, I hereunto affix my signature, this the 2nd day of August, A. D., 110 1920.

SANFORD E. MANNING.
